(57) **CLAIM**

The ornamental design for a display mount, as shown and described.

DESCRIPTION

FIG. 1 is a perspective view looking down on the front right side of a display mount showing my new design;

FIG. 2 is a top view;

FIG. 3 is a front view;

FIG. 4 is a right side view;

FIG. 5 is a left side view;

FIG. 6 is a back view;

FIG. 7 is a bottom view; and,

FIG. 8 is a right side view in environment.

The broken line showing of a display is for illustrative purposes only and forms no part of the claimed design.
